(57) **CLAIM**

The ornamental design for a clipper blade, as shown and described.

DESCRIPTION

FIG. 1 is a top, rear, left side perspective view of a clipper blade, showing my new design, shown with the main and secondary blades combined;

FIG. 2 is an exploded rear perspective view thereof;

FIG. 3 is an exploded front perspective view thereof;

FIG. 4 is a rear elevational of FIG. 1;

FIG. 5 is a front elevational view of FIG. 1;

FIG. 6 is a rear elevational view of the main blade, shown separately to show aspects of the design that are not clearly visible when combined;

FIG. 7 is a front elevational view of the secondary blade, shown separately to show aspects of the design that are not clearly visible when combined;

FIG. 8 is a top plan view of FIG. 1;

FIG. 9 is an exploded view of FIG. 8;

FIG. 10 is a bottom plan view of FIG. 1;

FIG. 11 is an exploded view of FIG. 10;

FIG. 12 is a left side elevational view thereof, the right side elevational view being a mirror image thereof; and,

FIG. 13 is an exploded view of FIG. 12.

1 Claim, 3 Drawing Sheets
